UNITED STATES PATENT OFFICE.

JOSEPH THEODORE SPEARS, OF NORTH AUGUSTA, SOUTH CAROLINA.

FURNITURE-SUPPORT.

Specification of Letters Patent.

Patented Oct. 16, 1917.

1,243,116.

Application filed January 31, 1914. Serial No. 815,796.

To all whom it may concern:

Be it known that I, JOSEPH THEODORE SPEARS, a citizen of the United States, residing at North Augusta, in the county of 5 Aiken and State of South Carolina, have invented certain new and useful Improvements in Furniture-Supports, of which the following is a specification, reference being had to the accompanying drawings.

10 This invention relates to certain improvements in furniture supports and has relation more particularly to a device of this general character adapted to be employed in connection with furniture adapted to be disposed substantially in rows and particularly school desks or seats; and the object 15 of the invention is to provide a device of this general character having novel and improved means whereby the desks or seats 20 may be readily and conveniently displaced, should any occasion therefor arise.

The invention consists in the details of construction and in the combination and arrangement of the several parts of my 25 improved device whereby certain important advantages are attained and the device is rendered simpler, less expensive and otherwise, more convenient and advantageous for use, all as will be hereinafter more fully set forth.

30 The novel features of the invention will be carefully defined in the appended claim.

In order that my invention may be the better understood, I will now proceed to describe the same with reference to the accompanying drawings, wherein—

35 Figure 1 is a fragmentary view in top plan of supports constructed in accordance with my invention in operative position, the desks or seats carried thereby being omitted; 40 Fig. 2 is a detail sectional view taken through an end bar of a support, illustrating a means whereby the same may be anchored in position;

Fig. 3 is a fragmentary longitudinal sectional view taken through one of the side bars, illustrating the means whereby the desks or seats may be secured thereto;

45 Fig. 4 is an enlarged fragmentary view partly in elevation and partly in section illustrating the means whereby adjacent supports may be automatically interlocked; and

50 Fig. 5 is a view similar to Fig. 4 but in side elevation.

As disclosed in the accompanying drawings, 55 1 denotes a support constructed in ac-

cordance with my invention and comprising the elongated side members 2 disposed in parallelism and in predetermined spaced relation and having their extremities tied or united by the cross members 3—3. At predetermined points intermediate their length, the members 2 are provided with the openings 4—4 in each of which is adapted to be mounted a small wheel or caster 5 whereby it will be seen that such support may be drawn across the floor or other supporting surface with convenience and facility. The members 2 are also provided, at predetermined points intermediate their length, with the openings 6 through which suitable anchoring members, as indicated at 7, may be passed for maintaining the school desks or seats D in operative position thereupon.

As is thought to be obvious, it will be readily perceived that normally the support and the desks or seats thereon are adapted to be maintained in a substantial permanent location and in order that the support may be held against accidental displacement, I find it of advantage to produce in the connecting or tie members 3 suitable openings 8, through which anchoring means as indicated at 9, may be passed to so engage the floor or supporting surface as to maintain the same immovable. As herein set forth, the fastening means 9 are herein shown as threaded members whereby the same may be detached from the floor or supporting surface with convenience and facility when it is desired to displace the support.

90 In practice, I find it of advantage to employ a plurality of supports, each of which being of predetermined dimensions and when such supports are assembled in operative position, I find it also of particular advantage to provide means whereby they may be interlocked and, as disclosed in the accompanying drawings, I set forth a means whereby such interlocking engagement is substantially automatic. As herein embodied, such means includes a plurality of expandible spring latches 10 projecting from one end of each of the longitudinal side bars of the frame of a support and adapted to be accommodated within suitable recesses or cavities produced in the adjacent end of each of the longitudinal side bars of the frame of the succeeding support. It is to be observed that the outer or free ends of the arms 10 are inturned in order to facilitate

90

110

tate the insertion of said arms within a socket. This construction is believed to be clearly shown in detail in Fig. 4. It is also to be noted that the recesses or cavities have their longitudinal walls inwardly and outwardly inclined whereby the locking action of the arms 10 when inserted within a socket is materially facilitated.

From the foregoing description, it is thought to be obvious that a furniture support constructed in accordance with an embodiment of my invention is of an extremely simple and comparatively inexpensive nature and is particularly well adapted for use by reason of the convenience and facility with which the same may be transported from one locality to another over its supporting surface when the occasion may so require and it will also be obvious that my invention is susceptible of some change and modification without material departure from the principles and spirit thereof and for this reason I do not wish to be understood as limiting myself to the precise arrangement and formation of the several

parts herein shown in carrying out my invention in practice.

I claim.

As a new article of manufacture, a portable foundation for furniture comprising a skeleton frame of substantially rectangular configuration, each of the longitudinal side bars of the frame having a socket formed in one end, and spring latches projecting from the opposite end of the side bar and adapted to enter the sockets of a second frame, the sockets having their longitudinal walls flared inwardly and outwardly and each of the spring catches comprising spaced spring arms having their free extremities flared outwardly, the free extremities of the arms being inturned to facilitate the insertion of the arms within the coacting socket.

In testimony whereof I hereunto affix my signature in the presence of two witnesses.

JOSEPH THEODORE SPEARS.

Witnesses:

Mrs. T. M. BUTLER,
Clara ANDERSON.
